UNITED STATES PATENT OFFICE.

JOHN THOMAS BAGBY, OF BOWLING GREEN, MISSOURI.

POLE-TIP FOR VEHICLES.

SPECIFICATION forming part of Letters Patent No. 425,848, dated April 15, 1890.

Application filed August 13, 1889. Serial No. 320,774. (No model.)

To all whom it may concern:

Be it known that I, JOHN THOMAS BAGBY, a citizen of the United States, and a resident of Bowling Green, in the county of Pike and 5 State of Missouri, have invented certain new and useful Improvements in Pole-Tips; and I do hereby declare that the following is a full, clear, and exact description of the invention, which will enable others skilled in the art to 10 which it appertains to make and use the same.

My invention relates to improvements in pole-tips, the object being the production of a simple, durable, cheap, and efficient device of the character mentioned.

15 To attain the desired object, the invention consists of a pole-tip comprising a cap or socket having an upward extension to receive the hook and a spring-actuated plate arranged in said extension and bearing against the 20 hook; and, also, the invention consists in the novel construction of parts, substantially as described and specifically claimed.

Figure 1 represents a perspective view of a device embodying my invention. Fig. 2 represents a vertical central sectional view 25 thereof, and Fig. 3 represents a perspective view of a modified form of the device.

Referring by letter to the drawings, A designates the cap, thimble, or socket adapted 30 to fit on the end of the tongue or draft-pole and formed with the upward open extension B, through which the usual hook C passes, and in the extension is provided a socket or recess D, in which is placed a spring E, the 35 upper end of which bears on the plate F, having the head or heads H for guiding and retaining the plate in place.

In the modification of the invention the 40 spring encircles the extension and operates in the same manner as the other form.

From the foregoing it is evident that the

plate is pressed against the hook and effectually retains the same in place, but, however, gives sufficiently to allow the proper movement of the hook and the proper detachment 45 thereof.

The points of merit of my device will be readily seen and appreciated, and are calculated to recommend the device as a much-needed and thoroughly practical article. 50

Having thus described my invention, what I claim as new, and desire to secure by Letters Patent, is—

1. A pole-tip consisting of a cap or socket having an upward extension to receive the 55 hook and a spring-pressed plate bearing against said hook, substantially as described.

2. A pole-tip consisting of a cap or socket having an upward extension to receive the hook, a plate bearing against said hook and 60 having retaining-heads, and a spring for pressing the plate against the hook, substantially as described.

3. A pole-tip consisting of a cap or socket having an upward extension, a spring carried 65 by said extension, and a plate arranged in said extension and adapted to be pressed against the hook by said spring, substantially as described.

4. In a pole-tip the combination, with the 70 hook, of the yoke or extension to receive the same, the plate in said extension having guiding and retaining heads, and the spring bearing against said plate, substantially as described. 75

In testimony that I claim the foregoing as my own I have hereunto affixed my signature in presence of two witnesses.

JOHN THOMAS BAGBY.
